NUT

Arthur R. Breed, Euclid, Ohio, assignor to The Lamson
& Sessions Co., Cleveland, Ohio, a corporation of Ohio

Filed Jan. 21, 1969, Ser. No. 15,411

Term of patent 14 years

Int. Cl. D8—04

U.S. Cl. D8—274

FIG. 1

FIG. 2

FIG. 1 is a view of a nut embodying my design looking at the top and two sides of the nut from one corner; and

FIG. 2 is a view looking at the bottom of the nut of FIG. 1.

The nut when viewed from the other corners is a manner corresponding to FIG. 1 will have the same appearance as in FIG. 1.

The characteristic feature of my design resides in the bulges which project outwardly from the sides of the nut at the outer ends of the cross slot and which taper inwardly from the bottom of the cross slot to plane of the nut sides in combination with the overall appearance as shown.

What I claim is:

The ornamental design for a nut, substantially as shown and described.
